IMPULSE TRANSMITTER

Léon Kardorff, Brussels, Belgium, assignor to Inventor Trust S. A., Luxemburg, Luxemburg

Application September 27, 1935, Serial No. 42,406
In France October 12, 1934

7 Claims. (Cl. 179—90)

This invention relates to an impulse transmitting device to be used more particularly in the automatic telephone systems and comprising means permitting to send out groups of predetermined impulses.

Most of the apparatus of the above kind are provided with code controller discs having a certain number of teeth which are grouped together and which cooperate with electric contacts. 10 Such apparatus require the use of discs having a relatively large diameter in view of the fact that the discs should be provided along their periphery with the number of teeth which is necessary for producing generally at least six or seven 15 series of ten impulses, separated by hollows corresponding to the periods of rest.

In order to avoid the above drawback it has been proposed among others to use apparatus capable of transmitting a large series of impulses 20 of which a few only are really transmitted by means of code controller discs which short-circuit certain impulses in order to compose the desired series.

In these devices, the members which emit the 25 impulses and those which effect the short-circuits must operate in perfect agreement with each other. As however, one revolution of the code controller disc corresponds to about a hundred revolutions of the transmitting member, the 30 code controller discs should be made with great precision, and this can be obtained with difficulty only in the practice; their manufacture and more particularly their fitting makes them very costly and fragile.

The present invention does away with the 35 above drawbacks and allows of obtaining a device for transmitting impulses which has smaller dimensions, whilst reducing to a large extent the precision required in the manufacture.

The apparatus for transmitting impulses according to the present invention is characterized in that the formation of the impulses, transmitted by any suitable device, is influenced by a movable member having a profile or outline, 40 the motion of the movable member being such that after a profile has acted to form a series of impulses, the movable member is placed again in a position similar to that at the beginning, for the formation of a new series of impulses.

The moving member is constructed so as to 50 have a profile consisting of one shape or of several identical shapes, the length of each shape being such as to correspond for a given speed to the duration of ten impulses followed by a certain period of rest.

On the other hand, the profile of the moving member is such that its portion which coincides with the transmission of ten impulses, has its various points progressively displaced relatively to each other.

The moving member has no influence upon the transmission of impulses except on a portion of its profile and this portion may vary. The length of this portion is determined by the position of a feeler which cooperates with a code 10 member.

Use is made preferably as a moving member of a rotating member effecting a complete revolution for each of the digits of the number which is to be formed.

However, use may be made of a moving member having a profile consisting of several identical shapes, of which one complete shape is used for each digit which is to be formed. In this case the moving member will effect for each digit 20 a fraction only of a revolution. The moving member may be a cylinder, or a cam, etc. It may form an element independent of the make and break device acting upon the contacts of impulses or it may act itself as a make and break 25 device.

An alternating motion or an oscillating motion may be imparted to the feeler. The latter is displaced towards the code members which may be either parts of a circle or sectors, or rectilinear toothed members or cam members and may act along their height and not along their length, as was hitherto the case.

The code members may be arranged on a plate 35 or on a ring or they may be distributed in groups upon several fittings. The latter may be fixed or they may be displaced by saccades underneath the feeler.

In order to make the invention well understood, an example of its carrying into effect 40 will be given hereinafter, which is more particularly applicable to the automatic telephone systems.

Figs. 1 to 4 relate to an impulse transmitter 45 for predetermined calls.

Figure 1 is a horizontal section made along the axis of an impulse transmitter comprising a rotating member having the shape of a cylinder and acting also as a make and break device 50 with contacts of impulses.

Figure 2 is a vertical section made along the line X—X of Figure 1.

Figure 3 is a development of the rotating cylinder.

Figure 4 is a section along the plane Z—Z of Figure 3.

Figure 5 shows a movable member having a profile with two identical shapes.

5 Figures 1 to 4 show an impulse transmitter in which the movable member consists of a rotating cylinder acting as a make and break device coacting with contacts of impulses. The said movable member effects a complete revolution 10 for each figure of the number to be formed.

The apparatus comprises a cylinder 1 adapted to rotate around its axis and on which are placed the names corresponding to predetermined numbers of telephone calls. The cylinder 1 rotates 15 between a rear plate 2 and a front plate 3, the latter being provided with a pointer 4 opposite which may be brought any of the names marked along the generating lines of the cylinder 1. Between the plates 2 and 3 is fitted, along the 20 axis of the apparatus, a shaft 5 which carries toothed wheels 6 and 7 which gear respectively with other toothed wheels 8 and 9, the wheel 8 being secured upon an intermediary shaft 10 whilst the wheel 9 is integral with a sleeve 11 25 capable of rotating freely around the shaft 10.

The wheel 8 is integral with a ratchet wheel 12 coacting with a pawl 13 which is integral with a box 14 containing a spring 15 secured on the one hand to the box and on the other hand to 30 the shaft 10. At the end of the shaft 10 is arranged a handle 16 adapted to place the spring 15 under tension.

On the other hand, the sleeve 11 adapted to rotate freely around the shaft 10 is integral with 35 a toothed wheel 17 gearing with another toothed wheel 18 mounted at the end of a sleeve 19 adapted to rotate freely around the shaft 5 and integral with a movable member 20 having the shape of a cylinder and provided at its periphery with ten 40 teeth 21 made of an insulating material and angularly displaced relatively to each other and spaced by intervals 22 (see Fig. 3). A portion 23 without teeth connects the tenth tooth to the first tooth.

45 The cylinder 20 comprises also a path 25 having a certain number of horizontal portions 26 connected with each other by means of inclined planes 27 (Fig. 3). The path 25 acts as a guide to an arm 28 carried by a member 29 adapted 50 to slide along an axis 30 secured to the rear plate 2. The member 29 is connected by means of arms 31 to a sliding block 32 which may be displaced along an axis 33 parallel to the axis 30 and also mounted on the rear plate 2. The 55 member 29 and the sliding block 32 are subjected to the action of springs 34 and 35.

Along the arms 31 are adapted to slide two supporting members 36 made integral with one another by means of a connecting piece 37 engaging between the arms 38 of a double fork 39 (see Fig. 2) of which the other end is provided with arms 40 coacting with a projection 41 integral with a sleeve 42 mounted on a fixed shaft 43. The sleeve 42, and therefore the projection 60 41, are capable of an angular displacement around the shaft 43, due to the action of an arm 44, the end 45 of which bears against a cam 46 mounted on the shaft 5. The said cam has a certain number of straight portions 47 connected with each other by means of inclined planes 48.

One of the supporting members 36 carries a 65 feeler 49 coacting with code members 50 having the shape of toothed blades arranged around 70 the movable member 20. The said code members

50 are maintained inside supports 51 which are integral with the outer cylinder 1. Impulse contacts 52 and 53 are mounted on a support 54 (Fig. 2) which is integral with the member 29. The device is completed by a speed regulator and by starting and stopping means, not shown in the drawings.

The apparatus works as follows:

When a number is to be connected, the corresponding name marked on the cylinder 1 is brought opposite the pointer 4 by rotating the cylinder. This rotation brings the corresponding code-member 50 within reach of the feeler 49.

When the cylinder 1 has occupied the desired position, a pressure is exerted on the handle 16, 15 which has for its effect to tension the spring 15. Whilst the pressure is exerted, the pawl 13 slides on the ratchet wheel 12. When the handle 16 has been released, the spring 15 which expands, carries with it the box 14 in a movement of rotation and the pawl 13 presses the ratchet wheel 12 and the toothed wheel 8 which is integral with it, thus causing a motion of the toothed wheel 6 and consequently of the shaft 5 and cam 46.

25 On the other hand, the toothed wheel 7 causes a rotation of the cylinder 20 which may be made of an insulating material, through the intermediary of the toothed wheels 9, 17 and 18. The rotation of the cylinder or movable member 20 has for its effect to free the arm 28 which at rest is situated upon the highest portion of the path 25. Under the effect of the springs 34 and 35 the feeler 49 rests against the first tooth of the code-member chosen. The height of the teeth 35 of the code members 50 is such that the feeler 49 allows the impulse contacts 52 and 53 to be influenced only by a given number of teeth of the movable member 20 corresponding to the number which is to be formed. As soon as the teeth 40 of the movable member act upon the impulse contacts, the arm 28 rests upon the path 25 and follows the horizontal portions 26 and the inclined portions 27 of the path until it is brought back to the starting position.

45 Whilst the movable member 20 has effected a complete revolution, the cam 46 has been displaced through a fraction of a revolution only. The end 45 of the arm 44 has followed the horizontal portion 47 and the inclined plane 48 and 50 is brought to the next horizontal portion. The displacement of the arm 44 acts through the projection 41 upon the fork 39 which displaces the supports 36 by sliding them along the arms 31. The feeler 49 comes thus opposite the next tooth of the code member 50 and the device 55 works in a similar manner for the next revolutions of the movable member 20.

It is obvious that the modes of construction 60 shown in the accompanying drawing have been given only by way of example. Concerning more particularly the movable member which effects a complete stroke for each digit to be formed, it is clear that use may be made of other devices, for instance of a rack or other member having an 65 alternating motion.

On the other hand, it is possible by means of a few small modifications, to interchange the movable members shown by way of example in the mode of construction, or even to make them 70 rotate in a direction opposite to that shown in the drawing if the space comprised between the first and the last horizontal portion has been made inclined.

What I claim is:

1. An impulse transmitter comprising in combination a cam-like member of invariable profile moving continuously and in such a manner that its position is analogous for the same digit of each group of impulses, means coacting with the cam-like member for producing impulses, code-members corresponding to a given number of groups of impulses, and a feeler moving with an alternating motion imparted by the cam-like member and having a stroke which is limited by the code-member so as to vary the number of impulses of each group, as set forth. 5
2. An impulse transmitter comprising in combination a cam-like member of spiral-shaped profile moving continuously and in such a manner that its position is analogous for the same digit of each group of impulses, means coacting with the cam-like member for producing impulses, code-members corresponding to a given number of groups of impulses and a feeler moving with an alternating motion imparted by the cam-like member and having a stroke which is limited by the code-member so as to vary the number of impulses of each group, as set forth. 10
- 20 3. An impulse transmitter comprising in combination a cam-like member of cylindrical shape the side surface of which is cut in a stepped way approximately along a helix, moving continuously and in such a manner that its position is analogous for the same digit of each group of impulses, means coacting with the cam-like member for producing impulses, code-members corresponding to a given number of groups of impulses, and a feeler moving with an alternating motion imparted by the cam-like member and having a stroke which is limited by the code-member so as to vary the number of impulses of each group, as set forth. 15
- 25 4. An impulse transmitter comprising in combination a cam-like member having an invariable profile with teeth, said cam-like member moving continuously and in such a manner that its position is analogous for the same digit of each group of impulses, contacts acted upon by the said teeth for producing impulses, code-members corresponding to a given number of groups of impulses, and a feeler moving with an alternating motion imparted by the cam-like member and having a stroke which is limited by the code-member so as to vary the number of impulses of each group, as set forth. 20
- 30 5. An impulse transmitter comprising in combination a cam-like member of invariable profile moving continuously and in such a manner that its position is analogous for the same digit of each group of impulses, means coacting with the cam-like member for producing impulses, code-members arranged around the same axis as the cam-like member, said code-members corresponding to a given number of groups of impulses and a feeler moving with an alternating motion imparted by the cam-like member and having a stroke which is limited by the code-member so as to vary the number of impulses of each group, as set forth. 25
- 35 6. An impulse transmitter comprising in combination a cam-like member of invariable profile moving continuously and in such a manner that its position is analogous for the same digit of each group of impulses, means coacting with the cam-like member for producing impulses, code-members corresponding to a given number of groups of impulses, a feeler moving with an alternating motion imparted by the cam-like member and having a stroke which is limited by the code-member so as to vary the number of impulses of each group, and means for varying the number of rotations of the cam-like member, as set forth. 30
- 40 7. An impulse transmitter comprising in combination a rotating cylinder with a name index marked on its outer surface and containing a cam-like member of invariable profile moving continuously and in such a manner that its position is analogous for the same digit of each group of impulses, means coacting with the cam-like member for producing impulses, code-members driven by the said rotating cylinder and corresponding to a given number of groups of impulses, and a feeler moving with an alternating motion imparted by the cam-like member and having a stroke which is limited by the code-member so as to vary the number of impulses of each group, as set forth. 35
